(Cl. D7—7)

To all whom it may concern:

Be it known that I, Ray J. Pastine, a citizen of the United States, residing in the city and county of San Francisco and State of California, have invented a new, original, and ornamental Design for a Sandal, of which the following is a specification, reference being had to the accompanying drawing, forming a part thereof.

Fig. 1 is a plan view of a sandal embodying my new design;

Fig. 2 is a bottom view of the same;

Fig. 3 is a side elevation of the same; and

Fig. 4 is a rear view of the same.

I claim:

The ornamental design for a sandal, substantially as shown.

RAY J. PASTINE.
